UNITED STATES PATENT OFFICE.

OLOF THOMPSON, OF NEW YORK, N. Y., ASSIGNEE, BY MESNE ASSIGNMENTS, TO SPLIT-DORE-BETHLEHEM ELECTRICAL COMPANY, OF NEWARK, NEW JERSEY, A CORPORATION OF NEW JERSEY.

MAGNETO GENERATOR.

Application filed February 15, 1919, Serial No. 277,229. Renewed June 18, 1923.

This invention relates generally to magnetos with rotating armatures used for igniting the charge in internal combustion engines, and it more particularly appertains to that type of magnetos which are equipped with primary and secondary windings.

Primarily, the invention has for its object to produce an improved magneto wherein the primary and secondary windings shall be separately mounted, so that they may be insulated from each other at all times and under all conditions, thereby precluding short-circuits and removing a prolific source of trouble in the running of the engine.

15 A secondary object is the production of a magneto of the type aforesaid having separate cores for the said windings located in the same magnetic field and subject to the generating action of the rotor, whereby the capacity of each core to carry an amplified amount of conductive wires is enhanced, while the respective windings are enabled to be placed in inductive relation to each other without increasing the size of the 20 apparatus.

A third object is to provide a high tension magneto in which the secondary winding is located exteriorly with relation to the primary winding on the armature, so that the windings may be applied to their respective cores with greater accuracy and celerity, and either one of the latter can be dismantled independently of the other.

25 A fourth object is the provision of a structure comprising a powerful primary winding on a rotatable armature cooperating with an equally efficient secondary winding held stationary with relation thereto, both windings being subject to the same magnetic flux and so disposed within the frame of the device that either one of them will utilize a space therein heretofore left unoccupied.

A fifth object is to devise a construction 30 of the character described including a core for the fixed secondary winding extending at substantially right angles to the axis of rotation of the armature that carries the primary winding and arranged centrally be-

tween permanent bar magnets standing on 50 opposite sides parallel therewith, the result obtained being that the lines of magnetic force are cut to the best advantage, and a protective enclosure is afforded for the windings.

55

A sixth object is so to design a magneto of the nature mentioned as to secure thereby an abundance of electric current; a hot spark; a compact assemblage of parts; convenience of adjustments; facility of access 60 to repair or renovate; adaptability to production by machine operation; practical elimination of manual fitting; and general dependability.

Other objects and advantages of the invention will become apparent as the specification proceeds.

With the aforesaid objects in view, the invention consists of the novel combinations and arrangements of parts hereinafter described in their preferred embodiments, pointed out in the subjoined claims, and illustrated on the annexed drawings, wherein like parts are designated by the same reference characters throughout the several 75 views.

In the said drawings,—

Fig. I is a longitudinal vertical section, showing a practical embodiment of the invention;

80

Fig. II is an end view of a current interrupter or contact-breaker included in the device;

Fig. III is an end view, looking from the left-hand side of Fig. I;

85

Fig. IV is a central vertical section;

Fig. V is a sectional plan, the section being taken on line V—V of Fig. I, looking downward;

Fig. VI is a similar section, on line 90 VI—VI of Fig. I, again looking in a downward direction;

Fig. VII is a diagram illustrating the relative positions of the primary and secondary windings; and

95

Fig. VIII is a similar view, representing the two windings connected up in series.

Described in general terms, the invention

may be said to include a two-fold magnetic field constituted by permanent magnets of the straight bar species placed in parallelism and united transversely at one end by a base 5 upon which the bars stand and by a bonnet overlying them at the opposite extremity. The centre of the field is occupied by a fixed core extending from the bonnet to one of a pair of oppositely disposed pole-pieces, the other of which is attached to the base. Between the pole-pieces revolves an armature carrying but one winding to wit, the primary. The fixed central core is surrounded by a secondary winding placed in inductive 10 relation to the primary winding on the armature. Both windings consequently are located in the same magnetic field and subject to the generating effect of the armature tho they are separated from each other. Located in an axial direction with respect to the armature is the mechanism for interrupting the flow of current thru the primary circuit. Adjacent to this mechanism is a condenser which controls the fluctuations of the interrupted current and is situated also in the plane of the armature. Disposed to one side of the latter named parts and approximately in alignment with the secondary winding is a device adapted to 15 convey the induced current therefrom and distribute it to the various spark plugs of the engine. The elements respectively associated with the primary and secondary circuits can be included therein either in separate groups or in serial relation.

The advantages of the invention as here outlined are best realized when all of its features and instrumentalities are combined in the one and same structure, but, useful 20 devices may be produced embodying less than the whole.

It will be obvious to those skilled in the art to which the invention appertains, upon becoming conversant with the details thereof, 25 that the same may be incorporated in several different constructions. The accompanying drawings, therefore, are submitted only as showing the preferred exemplification of the invention.

The improved form of the device herein disclosed rests as a whole upon a base A, which may be rectangular as shown, or of any other convenient shape and dimensions. This base, preferably, is formed with lips or 30 upwardly-projecting sides A¹, designed to retain in place a pair of bar magnets, to which special reference will be made hereinafter.

Fastened to the said base on the right-hand 35 side thereof, is a head B of non-magnetic metal, which in the present embodiment of the invention constitutes the driven end of the magneto. Within this head an oil-chamber B¹ is formed, to which leads an

oil passage B². The requisite lubricant is fed to the latter from an oil-cup B³, covered up by a lid B⁴.

On the left-hand side of the base A, and likewise fastened thereto, is another head C of non-magnetic metal, having a boss C¹, 70 that affords a bearing for a gear-shaft hereinafter described. The head C also contains an oil-chamber C², with an oil passage C³ leading to the same, which is fed by means of an oil-cup C⁴, provided with a lid C⁵.

From the lower half of the head C projects outwardly a housing D, designed to enclose the aforementioned contact-breaker or electric current interrupted. This part of the device, it is understood, consists of mechanical means adapted to cause a sudden interruption in the current flowing through the primary winding of the magneto, and simultaneously to give rise to a high tension current in the secondary winding, which is expended as a spark at the ignition point.

Against the housing D is held a condenser casing E, of which E¹ is the outer head. A resilient arm E² holds the outer head against the casing, and the latter to the housing. As represented in Figs. I and III, the lower end of this arm is attached to a stud E³, screwing into the bottom edge of the head C. An adjusting lever E⁴ takes over the casing E, and is employed to vary the relative positions of contacting elements of the interrupter so as to predetermine the time at which they should be separated. Similarly to the interrupter, the condenser is fitted to the primary circuit of the magneto, and serves to absorb the reverse current at the point of interruption, which it subsequently returns to the primary winding when the contact is re-established.

A distributor plate F is held against the head C, above the upper half of the housing D. A number of sockets F¹ are provided on this plate, each fitted with a plug F².

Preferably, the magneto is furnished with the usual form of H-section armature, comprising heads G G, held together by rivets or studs G¹, with a laminated centre section G² therebetween, the latter being composed, for instance, of soft iron laminæ adapted to reduce the internal resistance encountered by the lines of magnetic force passing through the armature. The before-mentioned primary winding, herein denoted by the reference character G³, is carried by the said armature heads G, over the said centre section G². According to the present invention, the primary winding is composed only of relatively heavy conductive wires, which are thoroughly insulated from one another, as well as from the exterior.

At the opposite extremities of the armature are two shafts respectively designated

by H and H¹, the former being at the driven end, and the latter at the other end. An enlargement H², or flange, is provided at the inner end of the shaft H¹, and also a separate flange H³ at the inner end of the shaft H. Both of the parts H² and H³ are held to the heads G, as by screws H⁴.

Ball-bearings I are provided to support the shaft H, within the lower part of the head B. Similar bearings I¹ are supporting the shaft H¹, in the corresponding portion of the head D.

The said shaft H¹ carries a pinion J. The latter is driven by key pins J¹, projecting outwardly from the flange or enlargement H². A nut J², engaging an external screw-thread on the shaft H¹, holds the pinion J against the said flange or enlargement.

A gear-wheel K is in meshing engagement with the pinion J, which is located under the same. This gear-wheel is mounted upon a hollow shaft K¹, journaled in a sleeve K². The latter-named element is carried by the boss C¹, previously herein mentioned as pertaining to the head C.

The interrupter or contact-breaker includes an actuating cam L, made of fiber and having a taper fit in the outer end of the shaft H¹, substantially as shown. Adjacent to this cam is a lever L¹, pivoted as at L², on the inner face of the condenser casing E. A roller L³ is carried by the lever L¹, in contact with the cam L. A contact-piece L⁴, such as a button, screw or the like, is also carried by the lever, and opposite the same is a corresponding contact-piece L⁵, adjustably mounted in an insulated block L⁶, projecting from the inner head of the condenser casing. The lever L¹ is held to its pivot L² by the free end of an arm L⁷, which is secured to a lug L⁸, on the said inner head of the condenser. A flat spring L⁹ is further anchored to an angular offset portion L¹⁰ of the same lever. The other end of the spring L⁹ is attached to a lug L¹¹, also projecting from the said inner head. Another spring L¹², preferably of U-shaped formation, affords a ground connection for the primary circuit. This spring has its free end in contact with the outer end of the shaft H¹ with which one terminal of the primary winding is connected, as by soldering it to armature G. A third lug L¹³, to which the other end of the spring L¹² is secured, extends from the condenser casing E. The cam L is drawn into the open outer end of the shaft H¹ by a bolt L¹⁴. A nut L¹⁵, engaged by the bolt L¹⁴, is provided at the inner end of this shaft, from which it is separated by a suitable insulation, as L¹⁶. To the nut L¹⁵ is connected the other terminal of the primary winding.

Within the casing E is placed the con-

denser proper, composed of internal layers 65 M. Connected with one side of the condenser is a resilient arm M¹, while the other side thereof is grounded through casing E. A holder M² is attached to the arm, and made to carry a carbon brush M³, in contact with the head of the bolt L¹⁴. The arm M¹ is also suitably connected electrically to the block L⁶.

A non-conductive arm N is held to the gear-wheel K, at or near the hub thereof, as 75 by screws N¹. This arm has a sleeve N², also of non-conductive material, but carries a conductive finger N³, held in position by a screw N⁴. The latter is formed with a hollow head in which is lodged a coil spring 80 N⁵, urging a plunger N⁶ against the head of a contact terminal N⁷. The plunger is carried by a sleeve N⁸. A holder N⁹ is formed with the outer end of the arm N, within which is fitted a conductive sleeve N¹⁰, constituting an extension of the conductive finger N³. Within the sleeve N¹⁰ is received a carbon brush N¹¹.

Contact blocks O are imbedded in the plate F of the distributor, at the inner side thereof. From these blocks extend posts O¹, onto which the plugs F² are screwed. On the same posts are also collars O², against which wires leading to the spark plugs are forced by the before mentioned plugs F². The carbon brush N¹¹ wipes over the blocks O as the gear K is being rotated.

Permanent, straight-bar magnets P are made to stand with their lower ends on the base A within the lips A¹. Overlying the upper ends of these magnets is a bonnet P¹, set in opposed relation to the base A, and fitted between the top portions of the heads B and C. Lips P², on the bonnet P¹, retain the magnets in position. The magnets P, it is understood, produce the field of force from which the initial or primary current in the magneto is derived. Coacting with the lips A¹ and P², to retain the bars P in position, are provided other lips B⁵ and C⁶ 100 on the heads B and C respectively.

Extending in a groove transversely across the bonnet P¹ are laminæ Q, held therein by a stud Q¹, upset endwise. Other laminæ Q² are carried in a groove transversely of the base A, and are included in the lower pole-pieces standing in operative relation to the laminæ G², to which particular reference was previously made. The laminæ Q² are secured to the base A by means of a stud Q³, upset at the ends. Opposite Q², are upper pole-laminæ Q⁴, that coact therewith in increasing the strength of the magnetic field.

A laminated core Q⁵ is formed as an upward extension of the upper pole-laminæ Q⁴ aforesaid, and on opposite sides of this core are vertically-disposed segments Q⁶, ris-

ing from a base Q^7 , integral therewith. These several parts Q^5 , Q^6 and Q^7 are secured together by headed studs Q^8 . The base Q^7 is separated from the laminæ 5 Q^2 through the interposition of non-magnetic pieces Q^9 .

The base A with the embedded laminæ Q^2 constitutes a lower pole structure of one polarity and the pole piece Q^4 , core extension Q^3 and bonnet P^1 with embedded laminæ Q , constitute an upper pole structure of the opposite polarity. These two pole structures taken with the permanent magnets P constitute the stationary field 10 structure of the generator.

Surrounding the core Q^5 is a secondary winding Q^{10} , consisting of numerous convolutions of fine wire. This winding is insulated from the core Q^5 and its lateral segments Q^6 , by a tube Q^{11} , passing through it. An outer, cylindrical wall Q^{12} also surrounds the secondary winding. Both the tube Q^{11} and outer wall Q^{12} may be formed integral with the base plate Q^{13} , upon which 20 they stand. The insulating tube Q^{11} is further engaged at its upper end by a centrally apertured cover Q^{14} , adapted to be screwed exteriorly thereon and forced down upon the upper edge of the cylindrical wall Q^{12} , 25 with packing Q^{15} intervening therebetween. The said tube Q^{11} , cylindrical wall Q^{12} , integral bottom Q^{13} , and cover Q^{14} constitute together a closed receptacle, providing a hermetic container completely enclosing the 30 secondary winding Q^{10} . By referring to Figs. I and IV, it will be seen that a sufficient space is left between the winding Q^{10} and the cylindrical wall Q^{12} to permit introduction therein of some compound adapted 35 to envelop the winding and insure its thoro insulation. As illustrated in Fig. I, a screw Q^{16} is connected with the lower end of the secondary winding Q^{10} and constitutes a ground connection therefor in the 40 base plate Q^7 . The upper end of this winding terminates in a connection Q^{17} coupled with the contact button N^7 whereby the induced current flowing thru the winding is 45 conveyed to the distributor. It will be noted 50 that the container for the secondary winding can be readily removed with it as a whole from its core and this can be done independently of the armature and primary winding.

55 Wires R lead from the plugs or binding posts of the distributor to spark gaps S , which are in turn connected to ground, as is also one end of the secondary winding Q^{10} . In the wiring diagram of Fig. VII the winding Q^{10} is connected to ground directly 60 while in that of Fig. VIII such connection is made indirectly through the primary winding G^3 .

65 Other conductors (indicated at T in Figs. VII and VIII, but made up of above-de-

scribed structural parts actually) connect the interrupter and the condenser in series. One of the conductors T may form part of a ground connection. In the diagram Fig. VII, the current tension at the spark gap is that derived from the secondary winding alone. Whereas, in the layout disclosed by Fig. VIII the current pressure is cumulative, in the sense that the two windings are connected up in series with the spark gaps, by the wires U and U^1 . Altho these two diagrammatic representations indicate that only one secondary coil is used, it is quite conceivable that the same can be divided into a plurality of similar coils, either connected or separate from one another, or that different leads may be taken out at various points from a single coil.

It will, of course, be understood that in the operation of my generator the generating effect on the secondary winding incident to the continued rotation of the rotor after the interruption of the primary circuit, serves to augment and sustain the current flowing in the secondary circuit in the same manner as in the prior direct high tension magneto generators in which the primary and secondary coils are wound on the same core.

Among the several advantages obtained by the construction hereinabove described the following may be noted:—Due to the arrangement of the primary and secondary windings on separate mounts, both of them receive the full benefit of the constant flow of the lines of force emitted by the permanent magnets, the flux being uninterrupted and continuously following its natural course along the permanent magnet bars and the coil carrying cores enclosed thereby. The secondary winding, being stationary with respect to the rotatable armature that carries the primary winding, is in the most favorable position for purposes of induction, and both windings are best situated to perform their respective functions. Inasmuch as the windings are coiled around separate cores, a larger quantity of the conductive wires can be used for either winding, and a magneto of given size thus wound will produce more current than can be obtained in devices where both windings are on the one armature. This method of winding, it will be observed, does not operate to enlarge or 100 complicate the construction, since the increased amount of conductor is lodged in space previously unoccupied.

To refer particularly to the secondary winding, the wire surrounding the core thereof may be machine wound, thereby minimizing cost of production and enabling the winding to be applied or removed without disturbing the armature winding. A better opportunity to insulate the working parts 115 efficiently from one another is also afforded.

Besides, the secondary winding being separate and stationary, is especially well adapted to be isolated within a casing of its own forming therewith a self-contained structure. By simply separating the bonnet P^1 from the core Q^5 , the coil Q^{10} can be removed from the core Q^5 without dismounting the rotor.

While a certain preferred embodiment of 10 this device has been shown and described, it will be understood that changes in the form, arrangements, proportions, sizes and details thereof may be made, without departing from the scope of the invention as 15 defined by the appended claims.

Having described my invention what I desire to secure by Letters Patent and claim, is:—

1. A device of the type specified including means for producing a permanent magnetic field, a single winding therein designed to generate an electric current, a separate winding therein for deriving an induced current from the first winding, and 25 means adapted to rotate one of said windings while the other remains stationary.

2. A device of the type specified including means for producing a permanent magnetic field, a rotatable armature, a primary 30 winding mounted alone thereon, a stationary core in inductive relation to said armature, and a single secondary winding carried by said core.

3. A device of the type specified including an armature carrying a single primary winding, a relatively fixed core supporting a single secondary winding in inductive relation to said primary, and means for rotating said armature with respect to said 40 core in a permanent magnetic field.

4. A device of the type specified including means for producing a permanent magnetic field, separate cores contained therein, single primary and secondary windings 45 mounted in inductive relation to each other upon said cores, and means for rotating one of the cores while the other one is maintained in a fixed position.

5. A device of the type specified including permanent bar magnets disposed in parallelism and coupled together at their opposite extremities, a rotatable armature and a fixed core occupying a central position intermediate of said bar magnets, and windings of the primary and secondary types respectively carried by said armature and said core in inductive relation to each other.

6. A device of the type specified including parallel bars permanently magnetized, 60 transverse connections for the ends thereof, an armature having a primary winding rotatable in proximity to one of said connections, a stationary core with a secondary winding extending from the opposite connection towards said armature in inductive

relation thereto, and opposed pole-pieces for the latter on the adjacent connection and upon said core.

7. A device of the type specified including a rotatable armature with a primary 70 winding thereon, a fixed core having a secondary winding disposed at substantially right angles to the axis of rotation of said armature, permanent bar magnets extending parallel to the longitudinal centre of 75 said core, and bridging pieces connecting up the opposite extremities of said bar magnets.

8. A device of the type specified including means for producing a permanent magnetic field, a rotatable armature having a 80 single primary winding, an interrupter in the plane of said armature connected up in the circuit of said primary winding, a fixed core with a single secondary winding separately 85 mounted thereon in inductive relation to the primary winding, a distributor operatively coupled up with the circuit of said secondary winding approximately in the plane thereof, and an igniter contained in the latter named circuit so as to be controlled by said distributor.

9. A device of the type specified including a rotatable armature with a primary winding, an interrupter actuated from said armature within the circuit of said primary winding, a condenser positioned in the same circuit in axial alignment with both the armature and said interrupter, a stationary core having a secondary winding located exteriorly from the armature and its winding in inductive relation thereto, an igniter contained in the circuit of said secondary winding, and a distributor driven from the armature controlling the induced current from the last named winding to said igniter. 100

10. A device of the character described including means for producing a permanent magnetic field, a rotatable armature with a primary winding alone thereon, a fixed core carrying a single secondary winding beside 110 said armature, said armature and core being disposed in said field, an interrupter in the circuit of said primary winding driven by the armature, a distributor actuated by the latter opposite said secondary winding so as to control induced current therefrom, and an igniter in the circuit of the last named winding receiving the current from said distributor in timed relation to said 115 interrupter.

11. A device of the character described including a permanent magnetic field comprising substantially parallel bar magnets, an armature with a primary winding alone thereon rotatable between the latter, pole pieces disposed on opposite sides of said armature, a core extending from one of said pole-pieces, a single secondary winding on said core, and connecting members coupling said bar magnets together and with 120 125

said core so as to complete the magnetic circuit.

12. A device of the character described including a permanent magnetic field comprising bar magnets located in substantial parallelism with one another, connections joining the opposite poles thereof, a core extending inwardly from one of said connec-

tions intermediate of said magnets, a single secondary winding around said core, pole-pieces disposed opposite the inner end of the core and the other one of the connections, and an armature with a primary winding alone thereon arranged to rotate between said pole-pieces.

OLOF THOMPSON.
